Attn:

UNITED STATES PATENT OFFICE.

HARRY A. BEST, OF CHICAGO, ILLINOIS, ASSIGNOR OF ONE-HALF TO H. A. BEST LAMP COMPANY, OF CHICAGO, ILLINOIS, A CORPORATION OF ILLINOIS.

DESIGN FOR A LAMP.

60,950.

Specification for Design.

Patented May 16, 1922.

Application filed August 19, 1921. Serial No. 493,759. Term of patent 3½ years.

To all whom it may concern:

Be it known that I, HARRY A. BEST, a citizen of the United States, residing at Chicago, in the county of Cook and State of Illinois, have invented a new, original, and ornamental Design for Lamps, of which the following is a specification, reference being had to the accompanying drawing, forming part thereof.

I claim:

The ornamental design for a lamp as shown.

HARRY A. BEST.
